UNITED STATES PATENT OFFICE.

FRANCIS P. HUGHES, OF PHILADELPHIA, PENNSYLVANIA, ASSIGNOR TO MUNCHEN, HUGHES & COMPANY, OF PHILADELPHIA, PENNSYLVANIA.

CIGARETTE CASE.

Application filed February 10, 1927. Serial No. 167,127.

The object of my invention is to provide a construction of cigarette case which shall be adapted to be carried in the pocket of the user and, therefore, be as compact in thickness as possible while, at the same time, of such shape and form that the cigarettes within the same shall be subjected to no pressure such as would injure them.

A further object of my invention is to provide the recessed space within the hinged sides of the case with pockets approximately occupying one-half the height of the recess and, at the same time, constructed with bellows folds along the bottom and extending up on the sides so that the wall of the pocket may expand outwardly at all portions with the same facility and thus retain the cigarettes in parallel vertical position without undue flattening pressure upon them at their ends which are received within the pocket.

With the above and other objects in view, the nature of which will be more fully understood from the description hereinafter, the invention consists in the novel construction of cigarette case, as hereinafter more fully described and defined in the claims.

Referring to the drawing: Fig. 1 is an interior view of my improved cigarette case when fully opened; Fig. 2 is an edge view of the same when closed; Fig. 3 is an enlarged sectional view through one of the sides, taken on line 3—3 of Fig. 1; Fig. 4 is a sectional view on line 4—4 of Fig. 1; Fig. 5 is an enlarged section of one end of Fig. 3; Fig. 6 is a perspective view of the inner backing wall; and Fig. 7 is a perspective view of one of the bellows pockets before being secured in place.

The casing consists essentially of two rectangular side frames hinged together and adapted to be held in closed relation by a suitable catch. Each side frame is provided with a pocket for receiving and supporting the cigarettes. As shown in the drawing, the two side frames are in all material respects identical and, therefore, the description of the details of one of such frames will equally apply to the other.

The side frame comprises a rectangular metallic frame 2 which is provided along one vertical end with hinging means 3 for connecting with the other side frame, whereas the opposite vertical side or free end is

provided with a portion of a suitable catch 55 4 whereby the two hinged side frames may be secured in closed relation, such as indicated in Fig. 2.

The metallic frame 2 is provided with a reinforced inner backing wall 5 which is made of a shape such as shown in Fig. 4, in which the edges 5^a are somewhat curved and unite in curved corners 5^c, so that this inner backing wall is slightly cup-shaped and, therefore, has more or less rigid resistance. 60 This inner backing is preferably formed of fibre board suitably shaped in dies and set under the application of heat and pressure, and may, if desired, be reinforced by an inner paper or other suitable layer 5^b of slightly less area. The use of this extra paper layer 5^b is to assist the inner backing retaining its cup-shaped form and thus insure a predetermined recessed form to the case. 65

The inner backing provides a suitable support for the inner lining 6 which may be of silk or other suitable material which will give artistic finish to the inner backing wall of the case, said lining being secured to the inner backing wall 5 adjacent to its perimeter, said attachment being preferably by stitching, as at 10. 70

Secured to the lower approximate half of the inner backing is a bellows pocket 7, the same comprising an outer flat wall bounded 85 by the bellows fold structure 8 at its two sides and also its bottom, so that it is quite flexible relatively to the frame 2 and the inner backing 5, whereby the lower portion of the said pocket may freely expand to provide in the bottom of the pocket substantially as much space as is provided by the expansion of the side edges of the pocket. 90

The bellows fold 8 terminates on the inner side in a flange 9 extending along the sides 95 and bottom of the pocket, and said flange portions are preferably extended beyond the outer wall of the pocket 7 and stitched to the inner backing 10 and its lining 6 by the aforesaid stitches 10, said stitching being 100 desirably formed back of the metal frame portion 2, so as to be hidden, for purposes of finish. Furthermore, the attaching of the bellows pocket to the inner backing at a point beyond the full available width of 105 the pocket permits greater flexibility of the pocket in the direction of its expansion than would be the case if stitching were made

immediately back of the pocket proper, and which would, in such case, shorten the length of the flange portion 9.

It will be understood that, if desired, when assembling the pocket 7 upon the inner backing 5 and its lining 6, prior to the same being applied to the metallic frame 2, the said inner backing, lining and pocket flange may be secured together by glue, to relatively position the parts, and whereby they may be subsequently stitched with less care in handling, but I do not limit myself to such mode of attachment.

For outside finish, the extreme outer cover 15 12 may be of leather or other suitable material which is stretched over the metallic frame 2 and also over the hinge, if so desired, and the perimeter of the said cover layer is suitably drawn over the metal frame 2 and tucked in, as at 13, under the same and between it and the space over the parts 9, 6 and 5, and cemented to said frame, so that it becomes rigidly attached thereto, as is clearly shown in Figs. 3, 4 and 5. A 25 suitable soft cotton or felt layer 14 may be interposed between the outer cover layer 12 and the inner backing wall 5, to give a softness to the outer cover and, at the same time, is a somewhat smoother appearance than if no such padding were employed.

The cigarettes are indicated at 15 and, from Fig. 5, it will be seen that the pocket 7 extends outwardly at the bottom by reason of the bellows fold just as freely as it would 35 extend outwardly at the side edges and, moreover, by slightly tilting the case, the bellows pocket and cigarettes will assume the position indicated in dotted lines with respect to the frame proper and which will allow the upper edges of the cigarettes to extend beyond the frame 2, so that they may be readily lifted out without crushing or injury. However, the recessed portion 7^a back of the pocket and in the space above it is 40 amply sufficient to receive and house the cigarettes when the case is closed, and even though there may be a slight compression of them, such compression will be uniform throughout their length and hence without 45 injury, such as would occur if the pocket 50 were rigidly held along its lower edge against free expansion, such as alone can be produced by a bellows fold.

By employing a pliable bellows fold along 55 the lower edge of the pocket as well as at the sides, the flexibility is sufficiently great to allow the weight of the cigarette to move into a suitable position for removal, as indicated in dotted lines in Fig. 5, but, at the 60 same time, there is no possibility of the cigarettes dropping out unless the case was inverted, and even under such circumstances, the cigarettes would not fall out unless the case was inclined sufficiently to induce the 65 end of the cigarette to clear the metallic

frame portion. In other words, I embody in my improvement, all the advantages of a pocket and, at the same time, provide such flexibility that no injury will result from undue pinching of the cigarette. These improvements permit the cigarettes to be easily inserted and removed while maintaining the cigarette in its perfect condition.

While I prefer to make the case as a duplicate holder of cigarettes, that is having 75 each of the case portions provided for receiving cigarettes, it will be manifest that where a relatively thinner case is desired, one of the hinged cover parts of the case may be devoid of the cigarette holding 80 pocket and the recess for receiving the cigarettes; as my invention, in a broad sense, is embodied in one of the side portions of the case irrespective of the particular shape or configuration of the other portion of the 85 case, and whether it is a holder of cigarettes or merely a closure to extend over the cigarette holding case portion.

It will now be apparent that I have devised a novel and useful construction which 90 embodies the features of advantage enumerated as desirable, and while I have in the present instance shown and described the preferred embodiment thereof which has been found in practice to give satisfactory 95 and reliable results, it is to be understood that I do not restrict myself to the details, as the same are susceptible of modification in various particulars without departing from the spirit or scope of the invention. 100

Having now described my invention, what I desire to secure by Letters Patent is:

1. In a case of the character stated, the combination of two parts hinged together so as to close upon each other, one at least 105 of which parts comprises a rectangular metallic frame provided with a backing whereby an interior recess is formed within the confines of the rectangular metallic frame, and a bellows pocket having its face of 110 greatly less area than the area of the recess and in which the height and width of said pocket are respectively less than the height and width of the recess within the confines of the rectangular metallic frame so as to be 115 collapsible and expansible into and out of the recess, the bellows extending along the bottom and sides of the bellows pocket and having bottom and side edge portions projecting beyond the boundaries of the pocket 120 and attached to the backing at the rear of the rectangular metallic frame.

2. The invention according to claim 1, wherein further, the width of the pocket approximates the horizontal width of the interior recess and the height of the pocket approximates one-half of the height of said recess, and in which also the lower boundary of the pocket embodies substantially the same degree of expansibility as the side 130

boundary edges thereof by reason of which the cigarettes are retained within the pocket without objectionable pinching or crushing of the lower ends thereof.

5 3. The invention according to claim 1, wherein further, the backing is formed of a stiff sheet pressed into cup-shaped form and having an outer enclosing cover extending over the rectangular metallic frame, and in 10 which further the flanges of the pocket are secured to the backing by means of stitching.

4. The invention according to claim 1, wherein further, the backing is formed of a 15 sheet of material pressed into approximate rigid cup-shaped form and further stiffened by an interior sheet of less area cemented to the cup-shaped side of the backing so as to extend near to the bounding edges of the 20 backing.

5. The invention according to claim 1, wherein the backing is formed of a sheet 25 pressed into shallow cup-shaped form and having a lining of textile material loosely stretched over the recess side of the backing, and wherein further, the flange portions

of the pocket are stitched to the backing and textile lining to form a rigid union.

6. In a cigarettes case of the character stated, the combination of two metallic 30 frames hinged together each of which has a backing so formed as to provide a recess within the confines of the metallic frame, and in which further, each of said frames is provided with the bellows fold pocket 35 having width and height respectively less than the width and height of the recess within the confines of the metallic frame, each of said pockets having an expansible bellows fold connection with the backing extending 40 along the bottom of the pocket and up each of its ends, whereby the pocket as a whole may be expanded or collapsed to the same degree, said pockets substantially meeting over their entire exposed areas when the 45 same are provided with cigarettes and the hinged portions of the case are closed one upon the other.

In testimony of which invention, I hereunto set my hand.

FRANCIS P. HUGHES.
